CLAIM

The ornamental design for an enclosure track, as shown and described.

DESCRIPTION

FIG. 1 is an isometric view of the enclosure track of the present invention.

FIG. 2 is an end view of the enclosure track of the present invention.

FIG. 3 is a side view of the enclosure track of the present invention.

FIG. 4 is a top view of the enclosure track of the present invention.

FIG. 5 is a bottom view of the enclosure track of the present invention; and,

FIG. 6 is an isometric view of the enclosure track of the present invention in condition of use showing a section of a broken line enclosure positioned within the enclosure track.

The enclosure track is shown broken away in order to indicate that a specific length of enclosure track forms no part of the claimed design.

The broken lines in the drawing are for illustrative purposes only and form no part of the claimed design.
